UNITED STATES PATENT OFFICE.

ALFRED MÜLLER, OF DOMÄNE RUHLEBEN, NEAR SPANDAU, GERMANY.

TARGET.

No. 926,955.

Specification of Letters Patent.

Patented July 6, 1909.

Application filed August 9, 1907. Serial No. 387,942.

To all whom it may concern:

Be it known that I, ALFRED MÜLLER, a subject of the King of Prussia, residing at Domäne Ruhleben, near Spandau, in the 5 Kingdom of Prussia, Germany, have invented certain new and useful Improvements Relating to Improvements in Targets, of which the following is a full, clear, and exact description.

10 Drop targets are known which are caused to fall over by the shock of a shot striking them, the connection between the target and its stand or support being automatically released by the shock. These targets have 15 partly the drawback that each is separately fixed on a post, and that after the target has fallen the post still remains visible to the marksman, and thereby may be mistaken for a mark.

20 Now the object of this invention consists in a drop target which is caused to appear and disappear in already known manner and which may be arranged at any suitable place independently of a post or the like.

25 According to this invention the target rests on a separate support or holder on which the parts serving for holding the target are fixed. The parts operating the release of the fixed target are perfectly independent of and separate from the parts on 30 the target itself which effect the holding of the target, and are combined on a metal plate attached thereto. This arrangement has for its object to increase the stability of 35 the target and also to simplify the construction of the target and to allow of its various parts being easily removed or exchanged.

40 Various forms of construction of the object of the invention are shown in the accompanying drawings, in which:—

Figure 1 is a front view of a row of drop head targets standing ready to be fired at and which are mounted on a pivotal double plate; Fig. 2 is a front view of a releasing mechanism in a set and locked position, mounted on an angle plate or equivalent arrangement; Fig. 3, is a side view of same; Fig. 4 is a front view of a knee drop target. Fig. 5 is a front view of a falling head target 45 with another form of construction of the releasing mechanism. Figs. 6 and 7 are respectively an elevation and cross section on an enlarged scale of this mechanism. Fig. 8 is a cross section of a falling target formed as

a knee and figure target, and Fig. 9 is another 55 form of construction of the target mechanism. Fig. 10 is a front view of the target holder; Fig. 11 a side view with inserted cross wood target; Fig. 12 a plan view of the target holder, omitting its vertical arm. 60

In the form of construction shown in Figs. 1-4, the target *a* is carried by a support piece or holder *n*. On this holder *n*, which on its part may be arranged at any suitable place, so that the target may be also employed for 65 making the occupation, for instance, of houses, windows, trees and the like, that is to say, the target-holder may be arranged at any suitable place, for instance, at windows, trees and the like, so that there may be obtained the illusion of occupied houses or 70 forests, which is very useful, a connecting hook *h* which serves as a locking device is attached and provided with a pressure spring *m* shown in Fig. 3, which serves for throwing 75 over the target to the front.

On the side of the target *a*, facing the marksman, a metal plate, for instance an angle plate *b* is fixed. On the horizontal arm of this angle plate, which also serves as 80 a stop for the connecting hook *h*, a striker *c* is pivoted. On the striker a contact or hooked arm *d* is provided which in the holding position fixes the connecting hook *h*. The striker is under the action of a striker 85 spring *e* the end of which is attached to the vertical arm of the angle plate and its other end to the hooked arm *d*. In the holding position the set screw *l* screwed through the angle plate serves as a support for the striker 90 *c*. For the purpose of correct adjustment this screw *l* may be screwed more or less into the plate *b*. The turning of the set screw *l* may for instance be effected by means of a pin which engages in a perforation in the 95 head of the stop, but it may be operated in any other suitable way. In order to obtain as small a contact surface as possible between the set screw and the striker, it is preferable to screw in the set screw at a slight inclination to the striker, or to bevel off inward the end of the screw.

The action on the target just described is as follows:—When the target is in its upright position the various parts of the locking device occupy the positions shown in Figs. 2 and 3. In this condition the target is held immovable in its holder, so that accidental

disengagement of the locking device is prevented even in a strong wind. When a bullet strikes the target its smart sudden blow causes a vibration of the target whereby the 5 releasing lever C is disengaged from its set screw L. The lever acting under the impulse of its spring forcibly strikes the connecting hook h upwardly, so that it no longer engages the part b. The target is then thrown for 10 wardly by its spring m.

In targets, the targets arranged in a row on the double bars o (Fig. 1) usually employed for appearing and disappearing targets, which bars may be raised from the broad side 15 position, up on edge, in known manner from the shelter, it has been found that on erecting the targets a violent vibration was caused which was capable of prematurely releasing the targets standing in the upright position 20 and causing them to turn over. The security against such an unintentional releasing of the targets is obtained by the striker being retained by any suitable device, which may be easily removed from the shelter. In the 25 present form of construction this is done by means of a locking wedge p (Fig. 2) inserted between the striker c and a bent up flap k located on the horizontal arm of the angle plate. These safety wedges—simple wooden 30 wedges of diamond section—are connected by short connecting cords with a main cord running into the shelter, by means of which main cord they may be pulled down without trouble. The wedges are in this way entirely 35 removed from the target. A uniformly correct position of the striker under the set screw is also insured by the insertion of these safety or locking wedges. In Fig. 1 the safety wedges are removed.

40 The invention may also be applied to knee or jointed targets, only the vertical arm of the elbow plate in this case is prolonged upwardly (Fig. 4), in order to make a stronger connection, and so to transmit better the 45 vibration caused by a shot in the upper part of the target, downward to the releasing place.

Further forms of construction of the object of the invention are shown in Figs. 5-9, 50 which constructions have for their object to increase the security of working of the mechanism of the target as far as possible and also to enable the mechanism to be employed in the most practically favorable manner for 55 knee and figure targets. A spring e' which operates the striker c' pivoted on the elbow plate is in these forms of construction formed as a spiral spring, and thus renders the vertical arm of the elbow plate shown in Figs. 60 1-4, superfluous. The free end of the striker c' is so bent up that it also serves in the holding position as an arm for latching the connecting hook h. It is also preferable as shown in Fig. 9, to attach the striker spring

e² directly to the striker c² by means of 65 riveting or the like. The simplification thereby obtained is evident. In the set position the striker rests against a stop l screwed from beneath through the target and angle plate, which stop may be screwed out and in 70 for the purpose of correct adjustment. If, in the arrangement shown in Fig. 2, a pull be exerted on the wedge for the purpose of releasing the lock in the direction there indicated, the wedge may easily become jammed. 75 In order to avoid this, in this form of construction, a stop or rather guide bar b² is provided on the angle plate b', which stop prevents the jamming of the wedge p under a pull acting in the direction indicated by the 80 arrow in Fig. 6. The mode of working of this stop or guide bar is evident without further explanation from the drawings. The angle plate is also provided with a tongue z at the place bordering the lower edge of the 85 slot for the connecting hook h, the full horizontal surface of which tongue is passed through the slot for the connecting hook. In this way as metal acts on metal, on the one hand the automatic penetration of the wood 90 of the disk by the connecting hook and thus the impairment of the certainty of the action is prevented, while on the other by the tongue z being suitably raised or depressed it is possible to adjust the connecting hook in 95 the simplest manner. In using the mechanism on knee and figure targets as shown in Fig. 8, the arm n' carrying the connecting hook h, is suitably prolonged and supported by a separate stay f. For the purpose of 100 erecting the targets with certainty and correctly, independent of the punctuality of the target attendants, the target has recesses at its front and underpart, which serve for receiving the target holders. In order to allow of the 105 target easily and unimpededly falling over in any case, the rear edges of the disk are in the present case beveled off, while the lower supporting angle or elbow is formed of sufficient width, and these edges are merged with 110 a rounding into the lower support surface resting thereon. In this way the target on being struck is caused to fall over by reason of the play obtained by its shape, and is prevented from sticking. Between the target 115 holder and its support, a piece of felt is placed (Figs. 7 and 8), in order to insulate the parts which are not intended to be affected by vibrations, so that for instance a shot striking the bar cannot cause the target to fall. 120

In the forms of construction hitherto employed, the use of wood targets of at least 20 millimeters in thickness was customary and the horizontal part of the target holders was formed accordingly. In order to allow of 125 the targets easily and unimpededly falling over, in each case the rear edges of the target were rounded and beveled, and the lower

carrying elbow of the target holder made somewhat wide. The use of the same target holder for the wood cross targets of about 5 millimeters in thickness very frequently employed nowadays has been found very defective and uncertain, as the comparatively thin wood cross targets have too much play in the broad foot of the target holder, more particularly in a lateral direction, and consequently could easily be released unintentionally. In consideration of this, the form of construction of the target holder shown in Figs. 10-12 is provided with a bar which can enter a slot provided in the cross wood target. In this way the target is protected on the one hand against lateral movements, and on the other hand this bar serves to a certain extent for centering the target to be erected thereon, in the same way as the recesses formed on the front side of the thick walled wooden disks.

In constructing a thin walled target *a* it is mounted in such a way on the target holder *n*² that its slot *t* stands over the bar *s*. In this way the target is prevented making lateral movements and may be employed with the same certainty of working as the thicker wood targets before mentioned. If the same target holder is to be employed, at will for thick and thin walled targets, of course the thick wood targets must also be provided with a suitably formed slot *t*. By means of the perforations *u* provided on the horizontal part of the target holder *n*² it is possible to hold the targets also with this part by means of an intermediate piece of felt insulated above upon the bar, and in consequence of this possibility the visible surface of the falling targets is substantially increased not only on the target stand but more particularly in marking occupied houses, trees and the like.

I declare that what I claim is:—

1. A falling target adapted to be upset when struck having a metal plate, a striker, a spring adapted to actuate said striker, a hook adapted to engage said plate and to be struck by said striker, and a catch device for said striker adapted to be released when the target is struck said striker, spring and catch device being mounted on said metal plate.

2. A falling target adapted to be upset when struck having a metal plate, a striker, a spring adapted to actuate said striker, a hook adapted to engage said plate and to be struck by said striker, and a catch device for said striker adapted to be released when the target is struck, said striker, spring and catch device being mounted upon said metal plate, and said catch device comprising a screw which is adapted to be adjusted so as to regulate the releasability of the target.

3. A falling target adapted to be upset when struck having a metal plate, a striker, a

spring adapted to actuate said striker, a hook adapted to engage said plate and to be struck by said striker, a catch device for said striker adapted to be released when the target is struck, said catch device comprising a screw which is adapted to be adjusted so as to regulate the releasability of the target, and wedges *p* adapted to prevent the release of said striker.

4. A falling target adapted to be upset when struck having a metal plate, a striker, a spring adapted to actuate said striker, a hook adapted to engage said plate and to be struck by said striker, a catch device for said striker adapted to be released when the target is struck, said catch device comprising a screw which is adapted to be adjusted so as to regulate the releasability of the target, and wedges *p* adapted to prevent the release of said striker, said wedges being entirely removable from the target, and having a flexible connection whereby they may be removed.

5. A falling target adapted to be upset when struck having a metal plate, a striker, a spring adapted to actuate said striker, a hook adapted to engage said plate and to be struck by said striker, and a catch device for said striker adapted to be released when the target is struck, said metal plate being provided with an upwardly extending prolongation adapted to transmit the vibration, caused by a shot striking the target, to the releasing device.

6. A falling target adapted to be upset when struck, comprising a supporting member having a hook-shaped member pivoted thereto and a falling member having means for releasing said hook-shaped member, and being separable from said supporting member, said releasing means comprising a striker, a catch device for normally holding said striker said catch device being screw-threaded so that it may be adjusted and a spring for actuating said striker.

7. A falling target adapted to be upset when struck, comprising a supporting member having a hook-shaped member pivoted thereto and a falling member having means for releasing said hook-shaped member, and being separable from said supporting member, said releasing means comprising a striker, an adjustable screw-threaded catch device for normally holding said striker, and a spiral spring for actuating said striker.

8. A falling target having a striker, a connecting hook adapted to be struck by said striker, and a striker spring directly connected with said striker, wedges *p* adapted to prevent the release of said striker, and guide bars *b*² adapted to prevent jamming of the wedges.

9. A falling target having a releasing device comprising a striker, a spring for moving

said striker, a hook adapted to be struck by said striker, and a tongue z beneath said hook, said tongue extending through a slot in the target and adapted to be adjusted by bending it up and down.

10. A falling target having a target holder n^2 provided with a cross-bar s on its horizontal arm to permit thin wall targets being used, said cross-bar being adapted to enter a

slot in the target to provide against lateral movement of the target.

In witness whereof, I have hereunto signed my name in the presence of two subscribing witnesses.

ALFRED MÜLLER.
